UNITED STATES PATENT OFFICE

HARRY A. DOUGLAS, OF BRONSON, MICHIGAN

ELECTRIC LAMP

Application filed October 23, 1929. Serial No. 401,724.

My invention relates to lamps which employ lamp receiving sockets and holders for the sockets. The invention is of particular importance where such a lamp is equipped 5 with a concave reflector which carries the holder whose bore is in register with an opening provided through the reflector. The invention has for its general object the provision of means whereby the lamp may be fixed 10 with respect to said holder and, where the lamp is equipped with a reflector, may be fixed with respect to the latter element, also. The invention finds particular use in connection with lamps having parabolic reflectors 15 and enables the fixed relationship of the lamp filament with respect to the parabolic axis on which the filament is preferably located. A lamp thus constructed will direct light in a fixed path with respect to the axis of the reflector, thereby avoiding difficulty now frequently encountered in the adaptation of reflecting lamps to automotive vehicles, bodily or other adjustment of the lamps having frequently been required when the users happen 20 to find that the light is improperly directed.

In my copending application Serial No. 403,613 filed October 30, 1929, I have broadly claimed a lamp receiving socket within a holder and smaller in cross section than the 25 holder, and means pressing the socket laterally against one side of the holder. The structure disclosed in the aforesaid copending application employs a concave reflector with respect to which the socket holder is 30 fixed, the bore of the socket holder being in register with an opening that is formed through the reflector to permit of the insertion of the base of an incandescent lamp. The structure of the aforesaid application is 35 also inclusive of spaced apart spacing means intervening between the holder and socket in the place at which the socket is pressed against the holder.

The structure of my aforesaid copending 40 application is inclusive of a spring, integrally formed with a holder, which presses laterally upon the lamp base and, through the intermediation of the lamp base, laterally upon the socket. In the structure of my present 45 invention I employ a spring which is sepa-

rately formed from the holder. This spring is preferably a coiled spring and passes through a lateral slot to effect pressure upon the lamp socket and, preferably also, upon the lamp base through which base the lateral 55 pressure is exerted upon the socket, whereby all of these elements are maintained in fixed relation.

In my copending application Serial No. 401,721 filed October 23, 1929, I have disclosed a socket holder having a cam formation positioned to be engaged by a pin or projection that is provided upon the socket, when the assembly of the holder and socket is being effected, to increase the spacing between 60 the socket and holder in the region of the projection, so that the projection may be brought into register with a lateral opening, in the socket, that is to receive the projection. In the device of the latter copending application 65 the widening of the spacing between the holder and socket is effected by shifting the socket laterally of the holder. In the device of my present application the portion of the holder having the opening is also a spring 70 and is also provided with a camming formation engageable by the projection upon the socket, the spring being laterally flexed by the projection when being directed to the 75 opening in the spring.

If the holder be associated with a reflector, the position of the lamp filament with respect to the reflector is assured, it being understood 80 that the lamp filaments of the incandescent lamps which are to be used in the structure 85 of my invention preferably occupy predetermined uniform positions with respect to the lamp bases. To further assure the precise positions of the lamps, I desirably provide V-shaped seats in the bayonet slots that receive 90 the bayonet pins upon the lamps, so that the lamps are brought to a uniform position relatively. The lamp socket, in the structure 95 of my invention, is preferably prevented from having any longitudinal adjustment, so that the spacing of the lamp filament from the reflector is fixedly determined. This construction obviates the necessity of a special design for the reflector which has hitherto 100 been proposed to procure the same lighting.

effect with the filament in different positions along the reflector axis. The invention, however, is not to be thus limited.

The invention will be more fully explained 5 in connection with the accompanying drawings, showing the preferred embodiment thereof, and in which Fig. 1 is a plan view with a portion of the reflector shown in section; Fig. 2 is a view from beneath, part of 10 the bulb being broken away; Fig. 3 is a side view; Fig. 4 is a sectional view on line 4—4 of Fig. 1; Fig. 5 is a sectional view on line 5—5 of Fig. 4; Fig. 6 is a sectional view on line 6—6 of Fig. 4; Fig. 7 is a perspective 15 view illustrating component parts of the structure in separated relation; and Fig. 8 is a sectional elevation taken through the axis of the parabolic reflector.

The lamp illustrated includes a housing or 20 back element 1 having a bracket 2 on its bottom side by which it may be assembled with the automotive vehicle or other support, as indicated. The housing or back 1 encloses a parabolic reflector 3 which is formed with a 25 grooved flange 4 at its forward end. This flange is pressed against a rim 5, provided upon the housing, by an assembling ring 6. This assembling ring also presses the light transmitting closure 7, usually of glass, 30 against a gasket 8 which is seated in the flange 4.

The generally cylindrical socket holder 9 has its forward end passed through a circular opening formed through the crown of 35 the reflector, in the embodiment of the invention shown. The forward end of the holder 9 is formed with flanges 10 and 11 between which the surrounding edge portion of the reflector is clamped, whereby the holder and 40 reflector are maintained coaxial, in the structure illustrated.

The generally cylindrical lamp socket 12 is held in assembly with and within the holder 9 by the means hereinafter set forth. This 45 socket is preferably formed with a single bayonet slot or channel 13 for receiving a bayonet pin or projection 14 upon the base 15 of an incandescent lamp. This bayonet pin is maintained in a V-shaped retaining seat 13' 50 of the bayonet slot by any suitable means, the V-shaped seat holding the lamp from rotative movement. The means illustrated is inclusive of a coiled spring 16 which surrounds a plunger 17 constituting a circuit 55 terminal and presses forwardly upon the plunger head 18 and rearwardly upon the flange 19 of a metallic guiding sleeve 20. This guiding sleeve is mounted upon an insulating disc 21 which is fixedly assembled with 60 and within the rear end of the socket 12. The plunger head 18 presses against a contact 22 which is carried by the generally cylindrical lamp base 15 which is made of insulating material. The lamp structure illustrated is 65 a so-called single pole structure, though the

invention is not to be thus limited. Where a single pole structure is employed, the contact 22 is upon the axis of the lamp base. A stiff leading in wire 24 establishes connection between the contact 22 and one terminal of the filament 25. Another stiff leading in wire 26 establishes a connection between the other terminal of the filament and the metallic sheath 27 which surrounds the insulating portion of the lamp base and, from the point of view 70 of my invention, also constitutes a part or enlargement of the lamp base. The body of the reflector, the holder 9, and the socket 12 are grounded and when the lamp is in place 75 the sheath 27 is also grounded as it has connection with the holder, as will more fully appear.

In carrying out my invention the cross section of the socket 12 is smaller than the bore of the holder 9 and the base of the lamp, inclusive of its sheath 27, is smaller, in cross section, than the bore of the socket.

Spaced apart spacing means intervene between the holder 9 and the socket 12. These spacing means are preferably in the form of 80 ribs 28 which extend longitudinally of the holder and socket. Each rib is desirably integrally formed with one of the elements 9 or 12, both ribs being shown as being integrally formed with the holder. The ribs 85 are spaced less than 180 degrees apart, preferably 120 degrees apart. The means for pressing the socket 12 against the holder 9 is desirably inclusive of a coiled spring 29 which surrounds the lamp base and passes through 90 registering slots 30 and 31, respectively formed in the holder and socket, into engagement with the lamp base, so as to press this lamp base laterally against the socket and to 95 press the socket laterally against the holder. The spacing ribs 28 serve to maintain the 100 socket parallel with the holder and in fixed relation to the axis of the reflector. Spacing ribs 32, which may for example, be provided upon the sheath 27 longitudinally of the lamp 105 base, intervene between such base and the socket, whereby the lamp base is maintained parallel with the socket. These ribs 32 are desirably also spaced 120 degrees apart.

The holder is formed with a lateral circular opening 33 in a spring tongue 34 which is integrally formed with the holder. This opening receives the pin or projection 35 that is provided upon the socket. The rear end of the spring tongue 34 is provided with a cam or wedging formation 36. This wedging formation is engaged by the projection 35 in the process of assembling the socket with the holder, whereby the spring tongue is deflected laterally to permit the projection to be 115 brought into register with the opening 33, wherupon the spring tongue returns to enter the projection within said opening. As the V-shaped bayonet seat 13' prevents rotative movement of the lamp the filament of the 120

lamp is accurately positioned with respect to the reflector, this position being predetermined if the filaments of all lamps to be used in my device are accurately positioned with respect to the lamp bases.

5 Changes may be made without departing from the invention.

Having thus described my invention, I claim:

10 1. The combination with a transversely slotted socket holder; of a transversely slotted lamp receiving socket within said holder and smaller in cross section than the bore of the holder; a lamp having a base received in said socket, this base being smaller in cross section than the bore of the socket, the slots in said holder and socket being in register with each other and with a portion of the lamp base; and spring means, separately formed from the holder, passing through said slots into engagement with the lamp base and pressing the lamp base against the socket and pressing the socket, through the intermediation of the lamp base, against the holder.

25 2. The combination with a socket holder; of a lamp receiving socket within said holder and smaller in cross section than the bore of the holder; and a coiled spring, separately formed from the holder, pressing the socket laterally against one side of said holder to position the socket with respect to the holder, said spring encircling the said holder and socket and being retained by having its free ends hooked together.

30 3. The structure of claim 2 wherein the holder is formed with a lateral slot through which the spring is passed to press upon the socket.

35 4. The combination with a socket holder; of a lamp receiving socket within said holder and smaller in cross section than the bore of the holder; a lamp having a base received in said socket, this base being smaller in cross section than the bore of the socket, said holder and socket having registering lateral slots that are in register with a portion of the lamp base; and a coiled spring, separately formed from the holder, surrounding the lamp base and pressing the lamp against the socket and pressing the socket, through the intermediation of the lamp base against the holder.

40 5. The combination with a socket holder having a portion formed into a spring and having a lateral opening in this spring; of a socket within said holder and having a lateral projection, said spring having a cam formation positioned to be engaged by the projection when the assembly of the holder and socket is being effected, the spring yielding to enable the projection to be passed into register with the opening whereupon the spring returns to enter the projection without in the opening.

6. The structure of claim 5 wherein the socket is of smaller cross section than the bore of the holder and the spring presses the socket against the opposite side of the holder, and wherein spaced apart spacing means intervene between the socket and holder at the place where the socket is pressed against the holder.

7. The structure of claim 5 wherein the socket is of smaller cross section than the bore of the holder and the spring presses the socket against the opposite side of the holder, and wherein spaced apart spacing means in the form of ribs extending along the socket intervene between the socket and holder at the place where the socket is pressed against the holder.

In witness whereof, I hereunto subscribe my name.

HARRY A. DOUGLAS.
